UNITED STATES PATENT OFFICE.

BURGOYNE JONES, OF HINSDALE, ILLINOIS, ASSIGNOR TO JAHN & OLLIER ENGRAVING COMPANY, A CORPORATION OF ILLINOIS.

PROCESS OF PREPARING ETCHED OR ENGRAVED PLATES.

1,276,226.

Specification of Letters Patent. Patented Aug. 20, 1918.

Application filed April 20, 1916. Serial No. 92,548.

To all whom it may concern:

Be it known that I, BURGOYNE JONES, a citizen of the United States, residing in the city of Hinsdale, county of DuPage, and 5 State of Illinois, have invented new and useful Improvements in the Processes of Preparing Etched or Engraved Plates, of which the following is a specification.

This invention relates to improvements in 10 the process of preparing etched or engraved plates, and more especially to the process of preparing a set of plates to be used together in printing in colors on a color printing press, of one of the types in ordinary 15 use.

It is well known that when impressions are taken in black and white from a single etched plate prepared by one of the well known processes such as the photo-engraving process, or the half-tone process, where 20 it is desired to make certain parts of the impression appear blacker than other parts, portions of the surface of the tympan roller are raised by pasting on it small pieces of 25 paper cut in the required shape. These are called "make-readies" and their effect is to cause increased pressure on the paper over certain parts of the printing plate to make the required impression. It is also well 30 known that where the printing is done in colors by one of the simultaneous processes of printing in two or more colors at one operation, by means of a single tympan roller with the impression rollers surround- 35 ing it, it is not feasible to place "make-readies" over the tympan roller since the high places thus formed would press against all of the impression rollers and spoil the effect desired. It is therefore necessary 40 in such work to prepare the impression plates with certain portions of their surfaces slightly raised above the other portions and this invention accordingly relates to a process for thus preparing such plates 45 with portions of their surfaces raised with respect to other portions and their entire surfaces etched or engraved as required for printing from them.

The improved process is illustrated in the 50 accompanying drawing, in which:

Figure 1 is a view illustrating one of the

plates as it appears after the first step in the process.

Fig. 2 is a similar view illustrating the same plate as it appears after a subsequent 55 step in the process.

Fig. 3 is a similar view illustrating the appearance of the same plate after a further step in the process.

Fig. 4 is a similar view illustrating the 60 appearance of the finished plate.

Fig. 5 is a diagrammatic sectional view 65 through a similar plate showing the raised places on its surface enormously exaggerated for the purpose of better illustration.

The process consists in first making the required number of photographic negatives according to the number of colors to be afterward used in the printing, the negatives being made through a perforated 70 screen on glass plates in a camera, with means employed to locate each plate exactly in the same place in the camera so that if the glass negatives are afterward superimposed corresponding points in the images 75 will register accurately with each other. Each of these glass negatives is then used to 80 prepare one of the metallic plates, the further process being the same for each one of the latter and being as follows: The surface of a copper plate is sensitized with a sensitizing solution and upon it is made a print from one of the glass negatives. This print is then developed, or fixed, and examined and the parts of the design selected 85 which it is desired to bring out afterward in denser color than the other parts, and these parts of the design are covered with a protecting cover such as asphaltum paint by means of a brush. The plate is then 90 treated with an acid bath to remove all of the sensitizing preparations and then to a bath in a solution of ferric chlorid, or its equivalent, to etch or cut down all of its surface except the parts which have been 95 protected by the paint. After this step in the process the plate would appear as shown in Fig. 1 with portions 1, 2, of its surface relatively raised and all the other portions of its surface lower and perfectly smooth. 100 The paint is then washed off, the entire surface of the plate re-sensitized, and another

print made on its surface with the same glass negative; the latter being registered exactly with the metal plate in the same position as was obtained for the first print. This 5 print is then developed, or fixed, and again examined and the parts previously covered with paint are again covered in the same manner, together with such additional parts as it is desired shall also be raised, but to a 10 less height than those first selected; after which the plate is again treated to an acid bath to remove all the sensitizing preparation and to a bath of ferric chlorid to etch or cut down all of its unprotected surface. 15 After this stage in the process the plate would appear as in Fig. 2, where the raised portions 1 and 2 are seen preserved, together with the slightly less-raised portions 20 3, 4. In this manner the plate may be repeatedly treated to lower its surface, leaving parts of it correspondingly raised to different relative heights according to the 25 strengths of impression afterward desired in the printing process; Fig. 3 illustrating the plate after a further treatment to an acid bath and an etching bath of ferric chlorid with protected portions of its surface relatively raised above the remaining portions.

After the desired number of treatments to 30 thus provide the relatively raised portions on its surface the entire plate is finally re-sensitized, printed and developed, or fixed, and is heated, or "burnt" as it is technically known in the process, to bake the sensitizing preparation or enamel with which it 35 has been prepared; and it is then treated once more to an etching bath of ferric chlorid, or its equivalent, to eat through the unbaked parts of the enamel and form the 40 innumerable small dots or points in its surface which are required for a subsequent printing process—this last step in the process of burning and etching the plate being performed in the same manner as has 45 been heretofore in common use.

The plate thus prepared will present the 50 appearance of Fig. 4 with certain portions of its surface raised with respect to other portions and with respect to each other; and with the entire surface etched into the small 55 dots and points which result from the original exposure of the glass plates through a perforated screen. Such a plate in cross-section will also appear as shown diagrammatically in Fig. 5, in which, however, for better illustration the contours are enormously exaggerated.

Although the process has been above 60 described particularly for the preparation of one of the metal plates, as for example the plate used in printing a blue color, it is intended that the same process shall be used for preparing each of the other plates; and if there is a part of the design which must

be emphasized by a relatively stronger mixture of two colors, as for example a green portion, the corresponding parts of the blue plate and the yellow plate must both be raised so that they will afterward cause these two colors to be both emphasized in 70 the same part of the design; whereas if a part of the design to be emphasized in stronger color requires only one of the primary colors, as for example red, the corresponding portion of the red plate alone 75 would be raised, but none of the others.

As ordinarily performed this process would employ copper plates, as they are most suitable for such an etching or photo-engraving process as is employed herein, 80 and after the metal plates are thus prepared they may be applied directly to the printing cylinders for the printing process; or they may be used as original plates and from them any number of duplicates made by 85 taking from each copper plate a lead mold and filling this mold by the familiar electrotype, or equivalent process, as is well known.

I claim as my invention:

1. The process of preparing an etchable or engravable plate to receive a design, which consists in first providing a plate with a portion of its surface relatively higher than another portion thereof according to 95 the relative position of the lights and shadows in the intended design.

2. The process of preparing an etchable or engravable plate to receive a design, which consists in first acting chemically 100 upon the surface of a plate to provide portions of the surface which are relatively higher than other portions thereof according to the relative position of the lights and shadows in the intended design.

3. The process of preparing an etchable or engravable plate to receive a design, which consists in printing the design upon the surface of a plate, providing portions of the surface with a protecting covering according to the relative position of the lights and shadows in the design, acting upon the unprotected portions of such surface to cut them away, and then reprinting the design 110 upon the plate.

4. The process of preparing an etchable or engravable plate to receive a design, which consists in making an impression of the design upon a plate by a photographic process, then protecting a portion of the surface by a chemical resisting covering according to the relative position of the lights and shadows in the design, then subjecting the plate to the action of chemicals to cut away unprotected portions of its surface and then 120 reprinting the design upon the entire surface.

5. The process of preparing an etched or

engraved plate which consists in making an impression of a design upon the surface of a plate by a photographic process, then protecting a portion of the surface by a chemical resisting covering according to the relative position of the lights and shadows in the design, then subjecting the plate to the action of a chemical to cut away unprotected

portions of its surface, then reprinting the design in the same position upon the surface ¹⁰ and then etching or engraving the design upon the plate.

In witness whereof I have hereunto subscribed my name this 14th day of April, 1916.

BURGOYNE JONES.
